[57] **CLAIM**

The ornamental design for a leading edge light for a motorcycle fairing, as shown and described.

DESCRIPTION

FIG. 1 is a top plan view of the leading edge light embodying my new design, as mounted on a motorcycle fairing;

FIG. 2 is a front elevation view thereof;

FIG. 3 is an enlarged front elevation view thereof;

FIG. 4 is a top plan view of FIG. 3;

FIG. 5 is a bottom plan view of FIG. 3;

FIG. 6 is a rear elevation view of FIG. 3;

FIG. 7 is a right end elevation view of FIG. 3;

FIG. 8 is a left end elevation view of FIG. 3;

FIG. 9 is a sectional view taken along line 9—9 in FIG. 3; and

FIG. 10 is a sectional view taken along line 10—10 in FIG. 3.

The broken lines in the drawing are for illustrative purposes only.
